United States Patent Office.

EDMUND YOUNGS, OF NEW YORK, N. Y.

Letters Patent No. 106,245, dated August 9, 1870.

IMPROVEMENT IN TUYERES.

The Schedule referred to in these Letters Patent and making part of the same.

To all whom it may concern:

Be it known that I, EDMUND YOUNGS, of the city, county, and State of New York, have invented a new Improvement in Tuyeres; and I do hereby declare that the following is a full, clear, and exact description of the same, reference being had to the accompanying drawing forming a part of this specification.

My invention relates to tuyeres, and consists in the relative construction of the cap and top plate, which will first be described in connection with those parts of a tuyere necessary to a full understanding thereof, and then fully specified in the summary or claim.

Figure 1 is a vertical central section, and

Figure 2, a plan view of a tuyere with my improvement applied thereto;

A is the air-chamber;

B, the bellows-tube; and

C, an inclined top-plate.

The plate C has an aperture on top to receive the hearth or cap, with recesses *ff* on opposite sides.

The cap D is provided with lugs *e e* on opposite sides, which pass through the vertical recesses *ff*, after which the cap is turned, and thereby firmly fixed in its place on the plate C.

A projecting flange of the cap overlaps the plate C on top, and forms the annular surface that rests upon

the tuyeres, while at the same time it protects the joint between the cap and plate from ashes and dirt.

g is a series of perforations, which admit the air to the fire at a number of points simultaneously, and thus produce an equable, uniform, and hot fire.

The under side of the cap is dome-shaped, to save an unnecessary waste of metal, and to form a subsidiary air-chamber. This cap is cast in a single piece, and can be furnished at a very limited cost, while it possesses the great advantage of being readily detachable by simply turning the lugs *e* to coincide with the grooves *f*.

I am aware of the patent granted to John Theat, October 2, 1866, in which is described a perforated hearth, convex on its upper surface, with a flange projecting outward from its edge, and resting on the upper surface of the wall of the air-chamber, and with a set-screw for fastening it to said walls; and I disclaim all right to any invention described in said patent; but

What I do claim as my invention is—

The construction of the recesses *f* in the annular plate C, and the lugs *e* on the hearth D, as and for the purpose described.

EDMUND YOUNGS.
